(57) **CLAIM**

The ornamental design for an oval lock, as shown and described.

DESCRIPTION

FIG. 1 is a front elevational view of the lock of the present invention showing my new design;

FIG. 2 is a rear elevational view thereof;

FIG. 3 is a right side view thereof;

FIG. 4 is a left side view thereof;

FIG. 5 is a bottom view thereof;

FIG. 6 is a top view thereof;

FIG. 7 is a perspective view thereof;

FIG. 8 is a rear elevational view of a second alternative embodiment of the present invention shown in FIG. 2 without the shackle blocker;

FIG. 9 is a perspective view of the second alternative embodiment shown in FIG. 8; and,

FIG. 10 is a top view of the second alternative embodiment shown in FIG. 8.

The broken line showing is included for the purpose of illustrating and forms no part of the claimed design.
